UNITED STATES PATENT OFFICE.

JAMES THOMAS CROW, OF ARKADELPHIA, ARKANSAS.

DESIGN FOR A VENDING BOOTH.

Application filed August 17, 1928. Serial No. 27,867. Term of patent 14 years.

To all whom it may concern:

Be it known that I, JAMES T. CROW, a citizen of the United States, residing at Arkadelphia, in the county of Clark and State of Arkansas, have invented a new, original, and ornamental Design for a Vending Booth, of which the following is a specification, reference being had to the accompanying drawing, forming part thereof.

In the drawings:
Figure 1 is a side view in elevation of the article, showing my new design; and
Fig. 2 is a plan view.

I claim:

The ornamental design for a vending booth, as shown.

JAMES THOMAS CROW.
